COMBINED FLASHLIGHT AND COMPACT, OR SIMILAR ARTICLE

Donald S. Hartwell, 134 Elton St.,
Providence, R.I. 02906

Filed Nov. 7, 1966, Ser. No. 4,572

Term of patent 14 years

(Cl. D86—10)

Fig. 1.

Fig. 2.

Fig. 3.

Fig. 4.

Fig. 5.

Fig. 7.

Fig. 6.

FIG. 1 is a bottom plan view of a combined flashlight and compact, showing my new design, the compact being in closed position,

FIG. 2 is a side elevational view,

FIG. 3 is a top plan view,

FIG. 4 is a front elevational view,

FIG. 5 is a rear elevational view,

FIG. 6 is a perspective view, the compact being closed, and

FIG. 7 is a perspective view, the compact being open.

I claim:

The ornamental design for a combined flashlight and compact, or similar article, substantially as shown.
